UNITED STATES PATENT OFFICE

2,526,016

HEATER

Basil D. Figg, Lansing, Mich., assignor to Motor Wheel Corporation, Lansing, Mich., a corporation of Michigan

Application May 23, 1946, Serial No. 671,744

5 Claims. (Cl. 257—137)

1

This invention relates to heaters and more particularly to circulating heaters having a forced air circulation.

The principal object of this invention is to provide a circulating heater having a fan therein for circulating air and means for distributing some of the air to points remote from the heater.

Another object of the invention is to provide a heater of this character having an air duct with a fan therein forming a portion of the wall of the heater, that portion being movable relative to the remainder of the heater to permit some radiation of heat directly from the heat exchanger.

These objects will more fully appear in the following specification when read in connection with the accompanying drawings, wherein:

Figure 1 is a front elevational view of a heater embodying the present invention;

Figure 2 is a cross-sectional view taken on substantially the line 2—2 of Figure 1;

Figure 3 is a cross-sectional view taken on substantially the line 3—3 of Figure 1;

Figure 4 is a top plan view of the heater with the top removed;

Figure 5 is a side elevational view of the heater;

Figure 6 is a fragmentary front elevational view of a modified form of the invention; and

Figure 7 is a fragmentary cross-sectional view taken on substantially the line 7—7 of Figure 6.

Figures 1 to 5 show a circulating heater embodying one form of the invention. The heater comprises an outer casing 10 formed of two upright side walls 11 and 12, a back wall 13, a front wall 14, a top wall 15, and a bottom wall or floor plate 16. Preferably these walls are all formed of sheet metal. Preferably the side wall 11 is imperforate. The side wall 12 is provided with a plurality of louvers 17 adjacent the bottom thereof. The top wall 15 is also provided with louvers 18. The bottom wall 16 comprises a sheet metal plate having an opening 19 therein for a purpose which will presently appear.

The front wall 14 of the heater has a relatively large rectangular opening 20 therein. The opening 20 is closed by a movable portion 60 of a duct for circulating air. This duct is made up of a front panel 21 and a rear panel 22 joined together by means of a perimetral wall 23. The interior of the duct is hollow. This movable portion of the duct is hinged to the front wall along one edge.

Adjacent the upper end of the duct is an air inlet opening 24 which communicates with the interior of the casing 10. Near the bottom of the outer panel of the duct are a plurality of louvers 25. These louvers provide an outlet opening for

2

air from the duct. The louvers may be adjusted in size or completely closed by means of a sliding closure plate 26.

A small centrifugal fan 27 is mounted with its inlet end adjacent the inlet 24. The fan 27 is attached to a shaft 28 of a small electric motor 29. The motor 29 is mounted on the outer panel 21 in any suitable manner.

In the bottom portion of the perimetral wall 23 is another outlet opening for air 30. This communicates with a fixed portion 61 of the above mentioned air duct in the front of the heater. The fixed portion of the air duct comprises a register box 31 having an opening 62 in its top communicating with the opening 30 in the upper movable portion of the duct. A conduit 32 communicates with the register box 31 and extends to the side wall 11 of the outer casing. The side wall 11 is provided with an opening 63 registering with the end of the conduit 32 remote from the register box. The last mentioned opening in side wall 11 is surrounded by a draw neck 32a. An air duct may be connected to draw neck 32a to conduct air to a remote part of the dwelling in which the heater is located.

Within the casing 10 is a conventional heat exchanger which in its present form is shown as being a vaporizing type oil burner 33 and a combustion chamber 34 thereabove. The burner and combustion chamber are mounted upon a sheet metal base 35 which is provided with small openings 36 therein to admit air to the burner for combustion. The air for combustion passes into the space beneath the base 35 through the opening 19 in the bottom wall of the heater and passes out of the combustion chamber 34 through an opening 64 at the top thereof which is surrounded by a drawneck 65. A pipe (not shown) may be attached to the drawneck 65 and extended through an opening 66 in the top wall 15 of the casing and to a chimney.

Also mounted within the casing is a fuel tank 37 and an oil control 38. Fuel is fed to the burner through a tube 39.

Preferably one or more sheet metal shields 40 are mounted within the casing between the tank 37 and fuel control 38 so as to shield these from excessive heat of the heat exchanger.

The operation of the heater is for the most part self-evident. Air for combustion is fed to the burner through the openings 19 and 36 and fuel is supplied to the burner from the fuel tank 37 through fuel control 38 and pipe 39. Combustion within the heat exchanger heats the walls 67 thereof, which in turn heat the air within the heater. Air is drawn in through the louvers 17 in the side wall and rises out through the louvers

18 in the top wall, as in a conventional circulating heater. When desired, however, the fan 24 can be operated, which will draw a large proportion of air from near the top of the heat exchanger into the duct in the front wall and force the same out through the louvers 25 in the front of the heater. If the louvers 25 are closed by the closure plate 26 the air will be forced down into the register box 31 and out through the conduit 32 into the associated air duct, if such is provided.

In some instances, it is desirable to dispense with the forced circulation of air but provide a considerable amount of radiant heat from the heater. In that case, the upper, movable section of the duct in the front wall can be swung open so that practically the entire front of the heat exchanger is exposed. In that case, a considerable quantity of heat is radiated directly into the room. Air is also circulated by gravity, in the usual way.

Figures 6 and 7 disclose a slightly modified form of the invention. In this case the upper movable portion of the duct in the front wall is provided with an opening 50 in its side adjacent the lower end. This opening is defined by a drawneck 51. The opening in the bottom of the duct is dispensed with.

A register box 52, which may be of any suitable cross-section, is located in the lower front corner of the outer casing with its upper end above the drawneck 51. The bottom and top ends of the register box are closed and an outlet opening 53 is provided adjacent the lower end of the register box. This opening can be connected to a suitable air conduit.

The upper movable section of the duct is hinged to the front wall in the manner described in connection with the previous modification. When the upper section of the duct is moved to close the opening in the front wall, the drawneck 51 extends into the register box, and air from the power blower in the duct is discharged into the register box and thence into the conduit at the side of the heater. When desired, the movable section of the duct can be swung to its open position and a considerable quantity of heat will be radiated directly from the front of the heat exchanger.

From the foregoing it will be seen that the invention provides a novel form of air circulating heater in which provision is made for forcing air directly into the room in which the heater is located or to rooms remote from the heater, or both. If desired, the power blower unit can be swung to open position to permit radiant heat to escape from the heater.

The particular construction disclosed also has an advantage that one buying such a heater can obtain the same with an ordinary flat plate as a closure for the opening in the front wall and use the heater solely as a circulating heater for a time, subsequently purchasing and installing a power blower.

The scope of the invention is indicated in the appended claims.

I claim:

1. A heater comprising an outer casing defined in part by upright walls, an air inlet in one of said upright walls, an air duct associated with said casing, said air duct comprising a section fixed within said casing and a section movable relative to said casing, said movable section when in closed position forming a portion of one of said walls and arranged to be moved from said wall to open position to permit access to the interior 70 75

of said casing, said movable section having an inlet opening communicating with the interior of the casing and an outlet opening communicating with the below mentioned inlet opening of said fixed section, said fixed section having an outlet opening communicating with the exterior of the casing and an inlet opening communicating with the outlet opening of said movable section only when the movable section is in closed position, a fan in said air duct for circulating air therethrough, and a heat exchanger in said casing.

2. A heater as defined in claim 1 wherein said air duct extends generally vertically, and said inlet opening for the movable section and the outlet opening for the fixed section are located adjacent the upper and lower ends of the ducts respectively.

3. A heater comprising an outer casing defined in part by upright walls, an air inlet in one of said upright walls, one of said walls having a relatively large opening therein, an air duct associated with said casing, said air duct comprising a section in fixed relation to said casing adjacent the lower end of said opening and a generally vertical section movable relative to said casing, said movable section forming a closure for said opening and arranged so that the sections of said air duct communicate with one another only when said movable section is disposed on said casing 20 so as to close said opening, said movable section having an air inlet opening communicating with the interior of the casing, said movable section having an air outlet opening, said fixed section having an air inlet opening communicating with the outlet opening of said movable section when the movable section is in closed position, said fixed section having an outlet opening communicating with the exterior of the casing, and a heat exchanger in said casing.

4. A heater as defined in claim 3 wherein a fan is mounted in said movable section of said duct, said fan having its intake side adjacent said inlet opening in said air duct.

5. A heater comprising an outer casing defined in part by upright walls, one of said walls having a relatively large opening therein, an air duct in said casing, said air duct comprising a section fixed within said casing adjacent the lower end of said opening and a section movable relative to said casing, said movable section forming a closure for the opening in said wall, said movable duct section having an inlet opening adjacent its upper end and communicating with the interior of said casing and said fixed section having an outlet opening communicating with the exterior of said casing, said fixed and movable sections having openings therein spaced from said inlet and outlet openings and arranged to register when said movable section is disposed so as to close the first mentioned opening, and means on said fixed section communicating with the exterior of said casing, a heat exchanger in said casing, and circulating means for circulating air through said air duct.
